DESIGN FOR A COMBINED BOTTLE AND CLOSURE

Robert B. Karoff, New York, N. Y.

Application May 30, 1945, Serial No. 119,805

Term of patent 3½ years

(Cl. D58—8)

To all whom it may concern:

Be it known that I, Robert B. Karoff, a citizen of the United States and a resident of the city of New York, in the county of New York and State of New York, have invented a new, original, and ornamental Design for a Combined Bottle and Closure, of which the following is a specification, reference being had to the accompanying drawings, constituting a part thereof, in which

Fig. 1 is a top plan view of a combined bottle and closure showing my new design;

Fig. 2 is a front elevational view.

Fig. 3 is an edge view;

Fig. 4 is a perspective view of the same.

The surface hatching on the bottle represents a gold color.

The back side of the bottle has a shape identical to the front side illustrated in Fig. 2.

I claim:

The ornamental design for a combined bottle and closure, as shown and described.

ROBERT B. KAROFF.
